and in Germany January 17, 1931

6 Claims. (Cl. 204—31)

It has already been proposed to utilize the very great rise of temperature produced locally by an electric arc to effect certain chemical reactions in a medium possessing great dielectric strength, such as a liquid hydrocarbon. Due to the insulating properties of such a medium, the production and maintenance of an electric arc presents serious difficulties, especially if alternating current is used, which otherwise possesses the advantage of easily attaining the necessary voltage by means of strong and simple apparatus having no collector. Numerous tests have shown that it is only possible to obtain stable operation when a no-load voltage is available which is four to five times higher than the load voltage between the electrodes. To realize such a difference between these two voltages, it is possible either to interpose, in the known manner, between the supply mains and the arc a suitably dimensioned self induction coil or to utilize as the independent source of supply an alternator having a very high potential drop.

But, even with this latter method of supply, apparatus must necessarily be used, the nominal power of which is much greater than the power actually absorbed in the arc, so that it is difficult to realize economically an installation having an acceptable efficiency. It has been discovered that a much more satisfactory solution from an industrial point of view consists in using between the electrodes in order to stabilize the arc, a series of oscillating discharges, permanently sparking over between the electrodes. This method, however, known under the term of "the pilot spark", only gives entirely satisfactory results in all respects when using certain arrangements which form the subject of the present invention. Experience shows that with these arrangements the no-load voltage necessary for excellent stability does not generally exceed twice the load voltage between electrodes; a still lower no-load voltage may even be used in certain cases. In any case, the nominal power required for electrical apparatus is always considerably reduced with respect to that necessary where the pilot spark is not used. To obtain the result in question, the first condition is to obtain per second a number of oscillating discharges which is relatively high multiple of the frequency of the alternating current supplied to the arc. If, for example, this latter frequency reaches 50 periods per second, good results are obtained with a thousand discharges per second. These discharges being produced in the known manner by the periodic charge of a condenser which is dis-

charged through a spark gap, it is thus necessary to add to the installation a special generator of ensuring the discharge in quest the desired frequency. Furthermore, as the applications particularly in view always correspond to the use in the arc itself of considerable the presence of this auxiliary generator do not form any appreciable inconvenience, its being limited to a fraction of the power required by the arc to produce the desired thermal effect. Under these conditions, an installation according to the invention may be constituted in accordance with the accompanying diagram drawing which illustrates an example of the invention. It is to be assumed that the arc maintained is to be struck between electrodes 1 and 2 in a medium having great dielectric strength, such as a liquid hydrocarbon, contained in a metal reservoir 3. This arc is supplied by an alternator 4 of industrial frequency, the potential drop of which has been suitably chosen. The electrode 2 is earthed to the container supply circuit being completed by the cable 5 which is earthed at 6. As the auxiliary generator there is used an alternator 7 of musical frequency (for example 500 to 1,000 periods per second) which supplies the primary of a transformer the secondary of which is connected on the one hand to one of the terminals of a condenser 9 on the other hand to the body of a metal box 10 which contains a rotary spark gap, the rotation of which rotates synchronously with that of the alternator 7. The box 10, the use of which will be explained later, is itself connected with the cable 5 and the earth 6; on the other hand the insulated electrode 12 is also earthed, while the insulated electrode 13 is connected to the primary of the transformer 8 which is connected to one of the terminals of the condenser 9. The other terminal of the condenser 9 is connected by means of an insulated cable 14 to the insulated electrode 1 of the container 3. It is easily understood that the condenser 9 is charged periodically by the condenser 7, the charging circuit being completed by the principal supply cable 15, the alternator 4, and the earth 5, 6. With regard to the periodic discharge through the gap which separates the electrodes 1 and 2, this is ensured by the passage of the rotor 11 in front of the fixed electrodes 12 and 13. Each passage determines two simultaneous sparks jumping respectively between each of these electrodes and the corresponding tooth of the rotor 11, thus producing a periodic short circuiting of the secondary of the trans-

ier 8. At each short circuit, the voltage at terminals of the condenser 9 is suddenly transferred between the electrodes 1 and 2, between which it is discharged if the voltage in tension is sufficiently high. Naturally, known means (not shown) are provided to suitably regulate the angular position of the teeth of the rotor with respect to the poles of the rotor of the alternator 7. On the other hand, the number of charges per second depends on the number of teeth of the rotor 11; it will generally be either half or double the frequency of the alternator. It should be noted that the use of a rotary spark gap is particularly advisable in the present case, as it is a question of ensuring regularly a series of discharges of relatively high energy following each other at very short intervals over working periods compatible with commercial use. The permanent production of very energetic oscillating discharges might present in practice serious inconveniences owing to the electromagnetic radiation which they may create. This radiation might, on the one hand, interfere in an inadmissible manner with the radio-electric receivers of the neighbourhood, and on the other hand, provoke the formation of coronas at various points of the installation; these coronas may become very dangerous when the installation is intended for the production of inflammable gases. According to one of the characteristics of the present invention, these defects are completely avoided on the one hand by arranging the rotary spark gap 11 in a metal box 10 which forms a screen, and on the other hand, by surrounding the case 14 by a metal tube 16 which constitutes a connection between the box 10 and the earth-cable 5. Due to this arrangement which may be completed if necessary by a metal hood surrounding the high tension terminal supporting the electrode 1, any troublesome or dangerous electromagnetic radiation is practically suppressed. On the other hand, a reactance coil 17 inserted in the cable 15 protects the alternator 4 against the passage of high frequency currents, its protection is completed on the drawing by a condenser 18, connected to the terminals of the alternator 4 as also an ohmic resistance 19 in series with a sparking gap 20. The latter system provides a very convenient method of ensuring that the alternator 4 is not subjected to dangerous excess voltages. Finally, the case 10 is preferably provided with a fan 21 driven by any suitable means which renews atmosphere of the case, the vitiated air escaping by the outlet 22. It is evident that the invention covers various forms in particular as regards the means of producing the pilot spark between the electrodes of the vessel 3; any other combination of high frequency circuits might be used based on the condition that a series of discharges can be furnished at a frequency of which is a high multiple of the frequency of the principal alternator 4. In conclusion, the invention obviously extends to the case where the source of supply of the arc is a polyphase one and furnishes either several monophasic arcs, or one polyphase arc.

What I claim is:

1. A method of striking and maintaining an electric arc between two electrodes situated in a medium having great dielectric strength, where the arc is struck and maintained between the electrodes by means of a pilot spark formed by a succession of high frequency discharges, the frequency of succession of these discharges be-

ing of the magnitude order of a musical frequency.

2. An apparatus for striking and maintaining an electric arc between two electrodes situated in a medium having a great dielectric strength which comprises a source of electrical current connected to said electrodes, an auxiliary circuit comprising a condenser, the said electrodes being connected to said auxiliary circuit, means for charging the said condenser and means for discharging said condenser across the said electrodes a number of times per second which corresponds to a musical frequency number. 80

3. An apparatus for striking and maintaining an electric arc between two electrodes situated in a medium having a great dielectric strength which comprises a source of electrical current connected to said electrodes, an auxiliary circuit comprising a condenser, the said electrodes being connected to said auxiliary circuit, an alternator of musical frequency distinct from the said source of electrical current for charging the condenser, and a rotary spark gap rotating synchronously with the said alternator for the discharge of the condenser across the said electrodes. 90

4. An apparatus for striking and maintaining an electric arc between two electrodes situated in a medium having a great dielectric strength which comprises a source of alternating current of low frequency connected to said electrodes, an auxiliary circuit comprising a condenser, the said electrodes being connected to said auxiliary circuit, an alternator of a frequency at least ten times higher than the frequency of the first named source of alternating current for charging the condenser and means for discharging the condenser across the said electrodes. 100

5. An apparatus for striking and maintaining an electric arc between two electrodes situated in a medium having a great dielectric strength which comprises a source of electrical current connected to said electrodes, an auxiliary circuit comprising a condenser, the said electrodes being connected to said auxiliary circuit, an alternator of musical frequency distinct from the said source of electrical current for charging the condenser, a rotary spark gap rotating synchronously with the said alternator for the discharge of the condenser across the said electrodes and a metal case enclosing said spark gap to suppress electromagnetic radiations outside. 115

6. An apparatus for striking and maintaining an electric arc between two electrodes situated in a medium having a great dielectric strength which comprises a source of electrical current connected to said electrodes, an auxiliary circuit comprising a condenser, the said electrodes being connected to said auxiliary circuit, an alternator of musical frequency distinct from the said source of electrical current for charging the condenser, a rotary spark gap rotating synchronously with the said alternator for the discharge of the condenser across the said electrodes, a metal case enclosing said spark gap to suppress electromagnetic radiations outside and a metal tube fixed to the metal case and surrounding the cable leading from one pole of the condenser to the insulated electrode in the metal container for the medium of great dielectric strength substantially over the whole length of said leading cable, this container and the said metal case being earthed. 125
